UNITED STATES PATENT OFFICE.

CECIL O. PHILLIPS, OF NEW YORK, N. Y., ASSIGNOR TO THE AMERICAN COTTON OIL COMPANY, OF NEW YORK, N. Y., A CORPORATION OF NEW JERSEY.

APPARATUS FOR MOLDING SOAP.

1,391,970.

Specification of Letters Patent. Patented Sept. 27, 1921.

Application filed June 5, 1920. Serial No. 386,912.

To all whom it may concern:

Be it known that I, CECIL O. PHILLIPS, a citizen of the United States, residing at New York, in the county of New York, State of New York, have invented certain new and useful Improvements in Apparatus for Molding Soap; and I do hereby declare the following to be a full, clear, and exact description of the invention, such as will enable others skilled in the art to which it appertains to make and use the same.

This invention relates to an improved apparatus for the molding and cooling of molten soap in a rapid and advantageous manner.

With the improved apparatus, the soap, while still molten, is charged into molds of approximately the shape of the desired cake, and passed through a cold salt solution or brine where it is cooled without being brought into direct contact with the brine. The soap cakes thus preliminarily cooled are then discharged from the molds and subjected directly to the action of the cold brine, whereby the cooling and hardening operation is very materially promoted. The soap cakes thus cooled are then preferably washed with fresh water to free the outer surfaces of the cakes from brine.

The improved apparatus of the invention comprises a receptacle for the brine used in cooling the soap, and a series of molds cylindrically arranged and rotatable in the brine bath together with means for filling the molds with molten soap, for protecting the soap while passing through the brine from direct contact therewith, and means for discharging the cooled soap from the molds.

The improved apparatus of the present invention, in certain of its novel aspects, includes the combination of a soap molding and cooling device, such as that above referred to, with a brine bath and suitable conveying means for continuously subjecting the molded cakes of soap to the direct action of the brine after they have been subjected to the preliminary molding and cooling.

The invention includes other features of improvement, which will further appear from the following more detailed description. In a copending application, Serial No. 386,913, executed concurrently herewith, an apparatus for molding soap is described, in which the molds for the soap

are arranged on a rotating table or support, whereby the cakes of soap are caused to travel in indirect contact with cold brine, and subsequently in direct contact with brine sprayed thereon. The present apparatus differs from that of the above mentioned copending application, in that the molds are arranged on a rotating drum, the soap cakes are directly subjected to the action of cold brine, and certain accessory devices are provided for removing the soap from the molds.

The preferred form of apparatus, embodying the invention, is illustrated in a more or less conventional and diagrammatical manner in the accompanying drawings, but it is intended, and will be understood, that the invention is illustrated by, but is not limited to, the specific embodiment thus illustrated and described.

In the accompanying drawings: Figure 1 is a sectional elevation taken on the line 1—1 of Fig. 2 and showing one form of the molding and cooling apparatus, certain parts being omitted;

Fig. 2 is a vertically transverse section taken on the line 2—2 of Fig. 1;

Fig. 3 is an enlarged sectional view of the right side of the apparatus of Fig. 1;

Fig. 4 is an enlarged sectional view of the left side of the apparatus of Fig. 1;

Fig. 5 is an enlarged sectional view, similar to part of Fig. 2, taken on the line 5—5 of Fig. 4;

Fig. 6 is a detail view showing the construction of the mold sections;

Fig. 7 is a detail view of one of the adjustable cam surfaces, taken on the line 7—7 of Fig. 3; and

Figs. 8 and 9 are a plan and elevation of part of the apparatus not illustrated in Figs. 1 and 4.

In the apparatus illustrated in the accompanying drawings, the tank for the cold salt solution or brine is indicated at 1 and is suitably supported by the supports 2 and 3 and by the shaft 4 which passes through the stuffing boxes 5 and is in turn supported by bearings 6, and supports 7. The shaft 4 carries the spider or wheel 8 having the radially arranged outer rim 9 which in turn supports the transverse arms 10 carrying the mold sections 11. Each mold section has three molds 12, of approximately the shape of the cake of soap to be molded, each mold having a piston 13 and piston rod 14.

with a roller 15 at its inner end. The arrangement of the mold sections and molds is such that they form a cylindrical series of molds rotating upon the shaft 4.

5 Above the cylindrical series of molds is the soap container 16 having steam jackets 17 for maintaining the soap at the proper temperature and preventing undue cooling thereof. The soap container is supported 10 by the upright supports 18 and has three filling compartments 19 each having a filling screw 20 therein operated by means of bevel gears 21 and 22. The shaft 23 carrying the gear 22 is in turn operated by the 15 ratchet wheel 24 and a pawl carried by the arm 25. This arm 25 is reciprocated by the operating rod 26, adjustably connected thereto, so that the operation of the ratchet can be controlled by the adjustment of the 20 rod 26 upon the arm 25.

Power is applied to the apparatus through the pulley 27 with which the worm 28 and the beveled pinions 30 and 33 are directly connected through the shaft 27^a. 25 The worm 28 drives the worm gear 29 which in turn causes the shaft 4 and the series of cylindrical molds carried thereby to be slowly but continuously rotated. The bevel gear 30 drives the bevel gear 31 which in turn causes the operating arm 32 to rotate and thereby reciprocate the rod 26 as above described. The bevel gear 33 drives the gear 34 attached to the shaft 35 which in turn operates the cams 38 through the bevel 30 gears 36 and 37. The pinion 39 on the shaft 35 meshes with a gear 40 on the shaft 41 which in turn operates the shaft 44 through the bevel gears 42 and 43. The shaft 44 carries the arms 45 arranged to 35 act upon the cooled soap cakes to remove them from the pistons.

A series of operating cams or cam surfaces, adapted to act upon the rollers 15, are suitably supported a short distance from 45 the series of molds. The cams or cam surfaces are arranged in series of three corresponding to the three series of molds, so that the rollers of each series will be similarly and simultaneously acted upon. The 50 cam segment 46 carrying the angle irons 46^a is thus supported by a transverse bracket 47 from the plate 48 which in turn is supported by the upright supports 18 and 49. The angle irons 46^a of the cam segment 46 55 provide a flat surface for the rollers 15. Near its right end this cam segment has an outer surface 52 as well as an inner surface 51 thus providing a groove 50 for the rollers and insuring that the rollers and the pistons 60 operated thereby are properly positioned. This groove is inclined inwardly for reasons hereinafter explained. The cam section 53 is pivoted at 54 and adjustably supported at 55 from the adjustable support 56. 65 This cam section likewise provides a double

cam groove. The cam section 57 is of similar construction and is supported by an adjustable support 58. The cam section 59 is adjustably supported by the slide 60 operating in the guide 61; the adjustment being 70 effected by adjusting screws 62 acting through the bell crank lever 63 and the connecting rod 64. The angle iron 65 which forms the cam surface is pivoted at 66^a and adjustable by means of the slots 66 and bolts 75 co-operating therewith. The cam surface formed by the member 65 is eccentrically arranged so that the right end thereof is somewhat nearer to the cylindrical molds than is the left end, for reasons hereinafter 80 explained. The cam section 67 has a centrally arranged outer cam surface 68 and has an adjustable slide support 69 similar to that above described.

Arranged below each of the three series 85 of molds, to the right of the soap container in Fig. 3, are spray pipes 70 for spraying the under surface of the molds with cold brine and thereby effecting a preliminary cooling thereof. Above the molds when in 90 the same position is a cooling jacket 71 having a brine supply pipe 71^b, and adapted for the flow of a cold salt solution or brine therethrough over the inner plate 71^a for cooling the outer portion of the soap in the 95 molds. Arranged circumferentially around the series of molds, while immersed in the brine, and protecting them from direct contact with the brine is an adjustable strap or band 72 supported at one end at 73 and adjustably supported at the other end by the 100 rod 74 and adjusting nut 75.

A slide 76 is arranged to receive the molded and cooled cakes of soap as they are discharged from the molds and a spray pipe 105 77 is arranged for spraying brine upon the slide or upon the cakes as they are discharged. Arranged to the left of the soap container 16 in Fig. 1 is a transversely arranged belt 79 carrying brushes, said belt being 110 supported by the bracket support 81 and driven in any suitable manner, as by a belt 80. These brushes are arranged to remove any adhering soap from the cylindrical mold sections 11 and the pistons 13, which, 115 as shown, may project somewhat above the surrounding surfaces.

The tank 82 is provided for subjecting the molded and preliminarily cooled cakes of soap to further direct cooling by the 120 action of cold brine. This tank has a suitable conveyer therein such as a screen conveyer 83 having cross cleats 84 and having sprocket chains passing over the sprockets 85. The conveyer passes under guide 125 sprockets or idlers 86 and then over the idlers 87 and into the tank 89 containing fresh water. It then passes under the sprockets 91, and then over the sprockets 92 to the drive sprocket 93 from which the 130

cakes of soap are discharged on to the apron or slide 97 and the conveyer 98 and carried thereby to the driver or to the place of storage or further treatment. The conveyer, 5 on its return, is guided by the idlers 94, 95, 88 and 96, the idlers 95 being adjustable to take up slack in the conveyer. Spray pipes 99 for brine are arranged over the tank 82 and spray pipes 100 for fresh water are ar- 10 ranged over the fresh water tank 89.

In the operation of the apparatus, the molten soap from the crutchers and compounded with the usual ingredients, is introduced into the soap container 16, and 15 is maintained therein by the steam jacket at the proper temperature. The cylindrical series of molds is slowly and continually rotated by means of the worm 28 and worm gear 29 and the three series of molds 20 are brought successively beneath the soap container. The pistons in each mold are kept flush with the surrounding surface of the mold sections, by the action of the double cam groove 50, upon the rollers 15, 25 when the molds are first introduced beneath the soap container. As the molds pass beneath the compartments 19, the pistons are drawn downwardly by the rollers operating in the double cam groove of the cam section 30 53 and soap is simultaneously forced down into the molds by the action of the screws 20. The intermittent operation of the screws, and the lowering of the pistons, are so timed that the soap is forced 35 downwardly into the molds at the same time that the pistons are drawn downwardly therein. The combined action results in the filling of the molds with the molten soap and with substantial avoidance of the oc- 40 clusion or inclusion in the mold of air bubbles or air pockets.

As the filled molds are rotated beyond the soap container, they are subjected to the cooling action of the cold brine spray 45 from the pipe 70 and to the cooling action of the cooling jacket 71, the spray acting upon the inner surfaces of the molds and the surface 71^a acting directly upon the outer surface of the soap in the molds. The 50 soap is thus given a preliminary chill before it is immersed in the brine in the tank 1. The molds are then passed down into the tank 1, but the soap in the molds is protected by the strap or band 72 from 55 direct contact with the brine. The cold brine thus acts through the band 72 and through the inner walls of the individual molds, without, however, coming into direct contact with the soap in the molds. The 60 soap is then rapidly cooled and the outer portions of the cakes rapidly solidified.

During the preliminary cooling of the soap in the molds an appreciable shrinkage takes place, but this is compensated for by 65 the eccentric arrangement of the cam sur-

face 65, that is, by making the lower right hand end of the cam surface (as shown in Fig. 3), somewhat closer to the cylindrical molds than the upper left hand end. As the rollers 15 pass over the eccentrically arranged cam surface, they are forced outwardly and in turn force the pistons outwardly a sufficient distance to compensate for the shrinkage of the cakes. The cam section 67 has its cam surfaces concentrically arranged and adjusted to keep the pistons and cakes of soap in proper position. The soap cakes are thus kept in contact with the walls of the molds and with the band or strap 72, so that effective cooling through the walls of the mold and through the strap or band will take place. 75

After the soap in the molds has become set and cooled, the outer surfaces of the cakes are exposed to the direct action of the cold brine as they pass upwardly above the end of the strap 72. As the molds come into alignment with the cams 38 these cams act upon the rollers and the pistons to force the cakes of soap out of the molds, and the 80 cakes are then separated from the pistons by the arms 45. The operation of the cams 38 and of the arms 45 is so timed that the cakes will be properly and effectively removed from the molds and pistons. The 85 cakes then pass down the slide 76, being assisted by the spray from pipes 77, and pass on to the conveyer screen or belt 83.

After the cakes of soap have been removed from the molds the pistons are forced outwardly, by the action of the cam 46 upon the rollers, so that they project somewhat beyond the cylindrical surface of the mold sections, and any adhering soap is then brushed from the pistons and 90 from the surface of the mold sections by the belt brush 79. Upon further rotation of the molds the pistons are drawn down even with the surrounding surfaces of the mold sections, by the action of the cam 95 groove 50 upon the rollers, and the pistons are held in this position when the molds first pass beneath the soap container.

It will thus be seen that the position of the pistons in the molds is controlled by 100 the various cam surfaces acting upon the rollers 15, and that the cam surfaces are adjustable to vary the action of the pistons. The pistons are thus forced outwardly, even with or slightly beyond the cylindrical surface of the mold sections, while the cakes of soap are being separated from the pistons by the arms 45 and while the pistons are being freed from adhering soap by the belt brush 79. The pistons are then kept flush 110 with the surrounding cylindrical surface while the molds are being passed beneath the edge of the soap container. The pistons are then drawn inwardly simultaneously with the forcing of the soap into 115 120 125 130

the molds by the screws 20, so that the molds are completely filled and the inclusion of air bubbles or pockets prevented. The eccentric arrangement of the cam surface 65 then causes the pistons to move outwardly, as the molds are being rotated, to compensate for the shrinkage of the cakes upon initial cooling, and the cam surface 68 keeps the pistons and cakes of soap in position 10 until the molds reach the lowest portion of their travel. Upon further rotation of the molds they are ultimately brought in alignment with the cams 38 and the cakes forced outwardly and separated from the 15 molds and piston, after which the operation is repeated.

The thickness of the cakes of soap can be varied, without changing the construction of the apparatus, by adjusting the cam surfaces 20 so as to vary the positions of the pistons in the molds during the operation. A thinner or a thicker cake of soap can thus be produced. It will be understood that the three cam surfaces for the three series of 25 molds can be simultaneously adjusted, so that the pistons of any three corresponding molds of the different series will be operated simultaneously and in the same way.

Immediately below the soap container 16 30 is a receptacle 101 for any soap that may escape around the pistons or otherwise. This soap is collected in the receptacle 101 and thus prevented from dropping into the brine. It can be scraped out of the receptacle, from time to time, as may be necessary. With proper construction and fitting of the pistons in the molds and with proper operation of the apparatus, little if any escape into the receptacle should take place.

40 After the cakes of soap have been separated from the molds they pass into the tank 82 and are carried therethrough upon the conveyer 83, preferably of foraminous material, such as wire cloth. The arrangement of this conveyer is preferably such that the cakes, in the case of floating soap, are partly or nearly immersed, and the upper surface of the soap is subjected to the cooling action of the spray from the spray 45 pipes 99. Where the soap is non-floating, it may be completely immersed therein. The soap cakes are thus exposed to the direct cooling action of the brine and are thus further cooled. The length of the tank 82 and 50 the period of time during which the cakes of soap pass through the brine can be regulated to give the desired cooling action.

55 After the cakes have thus been further cooled they are preferably washed or sprayed with fresh water to remove the adhering brine. This can be effected by passing the cakes of soap through the tank 89 containing fresh water and spraying the upper surfaces of the cakes with fresh water 60 from the pipe 100. This washing of the

65 cakes with fresh water is not necessary, but it is desirable for the higher grades of soap to free the surface from brine. A relatively short treatment with fresh water will usually suffice. The cakes of soap are then 70 carried by the screen or belt 83 to the conveyer 98 from which they are carried to a suitable drier or to a place of storage or further treatment.

75 The brine employed can be kept at the proper temperature by any suitable cooling means, for example, by the use of ammonia refrigeration apparatus. Brine may thus be cooled to a temperature of around 5 to 15° F, so that an energetic cooling action will 80 take place. With this temperature, it requires but a few minutes to affect the necessary molding and cooling of the soap cakes. As a result, the apparatus can be operated in a relatively rapid and continuous manner, so that it will have a large capacity.

85 The preliminary cooling of the soap while in the molds takes place without exposing the soap to the direct action of the brine, and the cakes of soap are thereafter directly 90 exposed to the cooling action of the brine and thereby further cooled. It will be understood that the apparatus of the present invention can be used for the molding and cooling of the soap without subjecting the 95 cakes of soap to subsequent direct cooling with brine, as well as in combination with the tank 82 or equivalent means for subjecting the soap cakes to such direct cooling action, but the capacity of the apparatus is 100 materially increased, and the cooling is effected in a particularly advantageous manner, by combining the preliminary cooling within the molds with the subsequent cooling by direct contact with the brine.

105 It will be evident that the molds may be of different sizes and shapes, for example, such that the resulting cake will be of oval, round, square, rectangular or other shape, by properly designing the individual molds and pistons.

110 Inasmuch as certain materials are corroded by the action of the brine, the apparatus should be constructed of material which is not acted upon, or, if constructed of materials which are so acted upon, the apparatus should be enameled or otherwise protected from corrosion. The parts of the apparatus which are immersed in the brine may thus be coated with enamel or they may 115 be made of materials which require no protection against corrosion.

120 Soaps of different character can be molded and cooled in the apparatus and according to the process of the present invention. The soap may thus be "floating" soap of high purity, or it may be laundry or other soap containing other detergent ingredients in admixture with the soap. The soap, prior to molding and cooling, is subjected to the 125 130

usual preliminary treatments, well understood in the art. The soap, after such preliminary treatments, and while still molten, is brought to the soap container 16 at a temperature of around 150 to 175° F, and charged into the molds at approximately the same temperature.

While the apparatus illustrated and described has three series of molds, it will be understood that the apparatus can be constructed and operated in a similar manner with the larger or smaller number of series. So, also, the specific construction illustrated and described can be varied without departing from the spirit and scope of the invention.

I claim:

1. An apparatus for molding and cooling soap, comprising a series of molds for individual cakes of soap cylindrically arranged and opening radially outward, means for filling the molds with molten soap, means for moving the molds through a cooling liquid and relatively with respect to the liquid whereby to subject the molds to the action of continuously changing liquid, and means in connection with the molds for protecting the soap from direct contact with the liquid.
2. An apparatus for molding and cooling soap, comprising a series of molds for individual cakes of soap cylindrically arranged and opening radially outward, means for filling said molds with molten soap, means for rotating said series of molds within a receptacle containing cooling liquid and for exposing all sides of the molten soap to the cooling action of such liquid, and means for ejecting the cooled soap from the molds.
3. An apparatus for molding and cooling soap, comprising a series of cylindrically arranged molds, each mold having a piston and operating rod, adjustable cam surfaces arranged to regulate the positions of the pistons within the molds while the molds are being filled with molten soap, other cam means for ejecting the cakes of soap from the molds when cooled, and means for moving the series of molds through a cooling liquid and moving relatively to the liquid, whereby to subject the molds to the action of constantly changing liquid.
4. An apparatus for molding and cooling soap, comprising a tank for a cooling liquid, a cylindrically arranged series of molds for individual cakes of soap arranged to rotate in a tank of cooling liquid, and through the liquid the individual molds opening radially outward, means for filling the molds and means within the tank for protecting the outer surface of the soap from direct contact with the cooling liquid while immersed therein.
5. An apparatus for molding and cooling soap, comprising a cylindrically arranged

series of molds arranged to rotate in a tank of cooling liquid, means for filling the molds and means for protecting the outer surface of the soap from direct contact with the cooling liquid while immersed therein, said means comprising a strap or belt held in contact with the said outer surface of the soap in the molds.

6. An apparatus for molding and cooling soap comprising a tank containing the cooling liquid, a cylindrically arranged series of molds rotatable therein, means for filling the molds with molten soap, and an adjustable band or apron arranged in the tank around the periphery of the series of molds to protect the soap contained therein from direct contact with the cooling liquid.

7. An apparatus for molding and cooling soap comprising a series of molds, means for filling the molds with molten soap, means for subjecting the molds to the action of a cooling liquid and for protecting the soap from direct contact therewith, means for discharging the cakes of soap from the molds and means for subjecting them to the direct cooling action of the cooling liquid.

8. An apparatus for molding and cooling soap comprising a series of molds, means for filling the molds with molten soap, means for subjecting the same to the action of a cooling liquid and for protecting the soap from direct contact therewith, an ejector for discharging the soap from the molds and means for bringing the ejector soap into direct contact with the cooling liquid, whereby the soap is subjected to a preliminary cooling operation in the molds and a subsequent cooling action in direct contact with the cooling liquid.

9. An apparatus for molding and cooling soap comprising a tank for the cooling liquid, a series of molds arranged to be immersed therein, means for filling the molds with molten soap, means for discharging the soap from the molds, a separate receptacle containing cooling liquid and means for passing the soap after removal from the molds through the cooling liquid in said receptacle.

10. An apparatus for molding and cooling soap comprising a tank for the cooling liquid, a series of molds arranged to be immersed therein, means for filling the molds with molten soap, means for discharging the soap from the molds, a separate receptacle containing cooling liquid, means for passing the soap after removal from the molds through the cooling liquid in said receptacle, and means for thereafter subjecting the soap to the action of fresh water.

11. An apparatus for molding and cooling soap comprising a receptacle for cooling liquid, a central shaft supporting a circumferential series of molds arranged to rotate in said liquid, each of said molds having a piston therein with an inwardly extending

piston rod, means for filling the molds with molten soap, means for protecting the soap in the molds from direct contact with the cooling liquid, a series of cams arranged to act upon the piston rods to assist in the filling of the molds with the molten soap and to maintain the soap under compression in the mold while cooling, and separate cam means for discharging the soap from the molds.

12. An apparatus for molding and cooling soap comprising a cylindrically arranged series of molds rotatable in a tank of cooling liquid, means for filling the molds with molten soap, each mold having a piston therein with an inwardly extending piston rod, cam surface arranged to act upon the piston rods to subject the soap to compression while it is being cooled, and a stationary surface around a periphery of the molds against which the soap is forced by said piston.

13. An apparatus for molding and cooling soap comprising a cylindrically arranged series of molds each having a piston with an inwardly extending piston rod, means for filling the molds with molten soap, means for subjecting the soap in said molds to the action of the cooling liquid, and an eccentrically arranged cam surface adapted to act upon the pistons to force the soap outwardly in the molds while it is being cooled.

14. An apparatus for molding and cooling soap, comprising a cylindrically arranged

series of molds rotatable in the cooling liquid, means for filling the molds with the molten soap, each mold having a piston therein with an inwardly extending piston rod, means for acting upon the piston rods to eject the soap from the molds, cams arranged to keep the pistons even with or somewhat above the outer cylindrical periphery of the molds, and a brush arranged to remove adhering soap from the outer cylindrical mold surface and from the pistons prior to the subsequent refilling of the molds.

15. An apparatus for molding and cooling soap, comprising a cylindrically arranged series of molds, rotatable in a tank of cooling liquid, said molds being open and exposed to the cooling liquid on their inner sides, a strap or band held in contact with the outer peripheral surfaces of the molds while immersed, thereby preventing escape of the soap and protecting the soap from direct contact with the cooling liquid, a soap container arranged above the series of molds, means for forcing soap into said molds as they come successively under the soap container, means for cooling the soap in the molds before the molds are immersed in the cooling liquid and for compressing the soap to compensate for contraction, means for discharging the soap from the molds, and means for removing any soap adhering to the molds prior to the subsequent molding operation.

In testimony whereof I affix my signature.
CECIL O. PHILLIPS.
